Primary Examiner — Cynthia R Underwood(74) *Attorney, Agent, or Firm* — King & Partners, PLC(57) **CLAIM**

The ornamental design for a slatwall hook, as shown and described.

DESCRIPTION

FIG. 1 is a perspective view of a slatwall hook, showing my new design.

FIG. 2 is a right side view of the slatwall hook of FIG. 1, and the left side view being a mirror image.

FIG. 3 is a top view of the slatwall hook of FIG. 1.

FIG. 4 is a bottom view of the slatwall hook of FIG. 1.

FIG. 5 is a front view of the slatwall hook of FIG. 1.

FIG. 6 is a rear view of the slatwall hook of FIG. 1; and, FIG. 7 is a perspective view of a slatwall panel utilizing the slatwall hook of FIG. 1.

The broken line portions of FIGS. 1-7 are included to show unclaimed subject matter only and form no part of the claimed design.

1 Claim, 3 Drawing Sheets(56)
